LATCH LOCK, PARTICULARLY FOR WORK-MEN'S TOOL BAGS AND ANALOGOUS CONTAINERS

Robert Rodger, Watford, England

Application December 9, 1944, Serial No. 567,338
In Great Britain December 14, 1943

2 Claims. (Cl. 70—63)

1

This invention relates to workmen's tool bags, cycle tool bags, and analogous containers, and it has for its principal object to protect the contents from unauthorised abstraction.

According to the invention a workman's tool bag, cycle tool bag, or analogous container is constructed with a cover provided with spring-urged key-controlled internal locking means functioning automatically when the container is closed.

To this end the cover of the container carries an external spring-controlled member connected operatively to internal retaining elements and adapted after being unlocked to be depressed for the purpose of imparting movement to said elements to disengage them and permit the cover of the container to be opened and access to be had to its interior and any external pockets which may be formed on the container.

In one constructional embodiment of the invention there is disposed above the longitudinal centre of the cover a handle member supported by two spring-controlled plungers slideable in vertical tubular guide posts each secured above an aperture formed in the cover, and within each tubular guide post is a plunger connected to a depending hook or latch loosely pivoted in the guide post and adapted normally to engage a fixed bar extending longitudinally of the container, whereby depression of the handle member serves to displace the plungers thereby to disengage the hooks or latches from the aforesaid fixed bar or lugs. A key-operated blocking member is associated with one or each of the plungers to prevent its displacement, this blocking member and the pertaining tubular guide post having co-acting tongues and grooves or equivalent which can be aligned to permit movement of the plunger only by angularly shifting the blocking member by means of the key.

The invention is illustrated, by way of example in the accompanying drawings, in which Figure 1 is a perspective view of a handbag with the cover closed, and Figure 2 is a similar view with the cover open, and Figures 3 and 4 are vertical sections, at ninety degrees from one another, of a form of the latch lock that is incorporated at one end of the handle of the bag.

Referring to Figures 1 and 2, the body 1 and ends 2 of the bag are here shown as formed of sheet metal worked over a stout wire frame (not shown) to which they are secured as by spot-welding. 3 is a shaped cover hinged to the body 1 and flanged at its ends as at 4 in order, when the cover is closed, to take over the upper extremity 5 of a hinged flap or closure such as 6

located at the top of a pocket such as 7 that may be disposed externally of each end of the bag for the reception in particular of oil cans. 8 is a stout metal frame disposed vertically in the central longitudinal plane of the body 1 to which and the ends 2 it is secured as by spot-welding, the upper run of this frame 8 constituting a bridge longitudinally of the open top of the body and being formed with two cranked portions at 9.

10 In alignment with the frame 8, and mutually opposite the cranked portions 9, the cover 3 is apertured and has formed on it or secured to it two bosses 11 above each of which extends a vertical tubular guide such as 12, Figures 3 and 4, 15 within which is slideable a plunger 13 operable against the tension of a compression spring 14 and carrying a depending stem 15 which passes through the apertured cover 3 and connects freely with the heel of a hook or latch 16 loosely 20 mounted about a pin 17 fixed in each boss 11, the toe of the latch 16 taking into the correspondingly opposite cranked portion 9 of the frame 8; and bridging the two plungers 13, pinned or otherwise secured thereto, is a handle 18.

25 When the cover of the bag is closed the tension in the springs 14 holds the hooks or latches 16 in engagement with the bridge member of the frame 8 by which the weight of the bag and its contents is borne when the bag is carried by hand, and in order to obtain access to the interior of the bag the handle 18 is pressed downwards against the springs 14 to rock the hooks or latches 16 about their pivotal centres and withdraw their toes from engagement with the 30 bridge member 8 after which the cover 3 can be 35 opened. However, in order to prevent unauthorised access to the contents of the bag one end of the handle 18 is provided with a key-operated lock now to be described.

40 The handle 18 (Figures 3 and 4) is provided with a keyhole to admit a key 38 and the plunger 13 is formed with a keyway for the same purpose and is pinned at 39 against rotation. At its upper end the tubular guide 12 has diametrically opposite V-notches 40 cut in it and between the top of the guide 12 and the underside of the plunger 13 a circular latch 41 is located which is formed with depending V-shaped projections 42 spaced correspondingly with the notches 40.

45 This latch 41, which is capable of both angular and axial movement, has an upwardly projecting lug 43 which engages a recess 44 in the plunger 13 and which serves the double purpose of providing an abutment for the ward or wards of the key 38 and also an anchorage for the upper end

of the spring 14 whereof the lower end is anchored to the shelf 21 between which and the latch the spring is confined.

In Figures 3 and 4 the handle is shown in the locked position and cannot be depressed in order to release the hook or latch 16 from the bridge member or frame 8 because the projections are not aligned with the notches 40. But when the key 38 is turned it bears on the projecting lug 43 and rotates the circular latch 41 until the said projections 42 thereon register with and are drawn into the said notches 40 whereupon the handle may be depressed in opposition to the tensile force of the spring 14 to release the hook or latch 16 and enable the bag to be opened in the manner already described. If then the key is left undisturbed the latching means will function automatically on closing the cover again, whereafter the key can be turned back and removed to prevent re-disengagement of the latch 15 without further use of the key.

I claim:

1. A latch lock, particularly for a workman's tool bag or an analogous container, comprising a tubular guide, an axially slideable cover for one end portion of the tubular guide, said cover having a keyhole, a latch loosely pivoted within the opposite end portion of the guide, a plunger mounted within the guide for sliding movement with the cover and pivoted to the heel of the latch, a blocking member mounted in the cover for sliding movement therewith and for independent angular movement by means of an ap-

propriate key inserted in said keyhole, said member and said tubular guide having co-acting projections and grooves, and spring means normally constraining the cover outwardly and the blocking member to an angular position in which said projections and grooves are out of alignment thereby to lock the latch.

2. A latch lock according to claim 1, the plunger having a recess and the blocking member having in engagement with said recess a projection serving the double purpose of providing an abutment for the wards of the key inserted in the cover keyhole and also as an anchorage for one end of the spring means.

ROBERT RODGER.
